Des. 67,467

UNITED STATES PATENT OFFICE.

EMIL A. MALHERBE, OF PHILADELPHIA, PENNSYLVANIA.

DESIGN FOR A HOUSING FOR MOTOR ATTACHMENT FOR MEASURING PUMPS.

Application filed September 28, 1922. Serial No. 3,835. Term of patent 14 years.

To all whom it may concern:

Be it known that I, EMIL A. MALHERBE, a citizen of the United States, residing in Philadelphia, Pennsylvania, have invented a new, original, and ornamental Design for Housing for Motor Attachment for Measuring Pumps, of which the following is a specification, reference being had to the accompanying drawing, forming part thereof,

in which the figure is an elevation of the housing for motor attachment for measuring pumps.

I claim:

The ornamental design for a housing for motor attachment for measuring pumps, as shown.

EMIL A. MALHERBE.
